CLAIM

The ornamental design for a ceiling fan as shown and described.

DESCRIPTION

FIG. 1 is a bottom perspective view of a ceiling fan showing our new design in a first operational configuration.

FIG. 2 is a bottom perspective view of the ceiling fan of FIG. 1 in a second operational configuration.

FIG. 3 is a bottom perspective view of a ceiling fan showing a second embodiment of our new design in a first operational configuration; and,

FIG. 4 is a bottom perspective view of the ceiling fan of FIG. 3 in a second operational configuration.

The broken lines depict the boundary of the claim that forms no part thereof.

1 Claim, 4 Drawing Sheets
